GARMENT STORAGE BAG

Samuel J. Johnson, West Chester, Ohio, assignor to Clopay Corporation, Cincinnati, Ohio, a corporation of Maryland

Application December 9, 1940, Serial No. 369,259

1 Claim. (Cl. 206—7)

This invention relates to a garment storage bag formed from paper or like material and is particularly concerned with a sight opening formed as an integral part of such a bag.

It has long been recognized that in a garment storage bag the provision of a sight window in the face surface of the bag is of decided advantage in enabling the user of the bag to determine which garment has been sealed in each particular bag.

Since the purpose of garment storage bags is to protect garments in storage against dust, dirt and insects, bags of this type are usually sealed with particular care and, once the seal has been broken, or the bag torn, its utility is greatly reduced. For this reason it is advantageous to provide a sight window in which the transparent sheet is tightly secured in place and adapted to stay that way.

There have been numerous objections to sight windows as they have been constructed in the past. Usually they have consisted merely of a sheet of transparent paper pasted either on the inside or outside of a preformed aperture in the side of the bag. It is difficult to form a tight bond by adhesive between a sheet of paper having a slick transparent surface and an ordinary sheet of paper. Folding or bending of any kind tends to cause the sheets to separate and forms a gap between which dirt and insects may sift. It is particularly difficult to secure a transparent sheet to the conventional printed outer surface of a garment storage bag because the ink used in the printing is of a greasy nature and makes it difficult, if not impossible, to obtain a strong bond between the bag and the transparent window pane. Obviously, it is a somewhat more difficult manufacturing operation to secure the transparent sheet to the inner unprinted side of the bag nor would it adhere well if so positioned because of the strains to which it would be subjected.

Another objection to the conventional construction of sight windows is found in the fact that such a window permits light constantly to pass through the opening and, in the case of long exposure, as when a garment bag has been hung in a sunny room or store window, it frequently happens that a portion of the garment corresponding to the size of the sight window is faded. This practically ruins the entire garment.

The sight window construction of the present invention corrects the difficulties just discussed. Instead of attaching the transparent sheet directly to the surface of the bag, either within or

without, it is attached to a more or less rigid frame portion and this frame portion is, in turn, fastened to the bag. Since the frame portion is quite rigid it will not be subjected to the bending and twisting to which the bag itself is subjected and the transparent sheet will remain firmly secured to its under surface. A secure bond can then be formed adhesively between the frame portion and the bag itself. The frame portion preferably is of relatively stiff paper, paperboard or like material.

In order to prevent the fading of garments exposed through the sight window the invention contemplates a flap preferably formed integrally as a part of the frame and adapted to be opened for a view of the interior of the bag or closed to shut out light during the period when the bag is in use.

One object of the invention therefore has been to provide a sight window for a garment storage bag in which the transparent window covering is maintained firmly in position by attachment to a frame member which is in turn attached to the bag.

Another object has been to provide a sight opening for a garment storage bag which can be protected at will by means of a flap adapted to close the sight opening.

Another object has been to provide means for readily lifting such a flap and, when desired, securing it in closed position.

Another object has been to provide a sight opening for a garment storage bag which is of simple yet effective construction and which may be conveniently added to the bag by inexperienced hand labor.

Other and further objects and advantages will be apparent from the further and more detailed description of the invention when considered in conjunction with the drawing in which:

Figure 1 is an elevation of a portion of a bag which includes sight opening means of the type of the invention.

Figure 2 is a front elevation of the sight opening means with portions thereof broken away to better illustrate construction.

Figure 3 is a sectional view along the line 3—3.

Figure 4 is an elevation of the sight opening means with the flap in raised position.

In Figure 1 a conventional garment storage bag is indicated generally at 1. A hanger seal is indicated at 2 and a conventional hanger hook at 3. The frame which is characteristic of the sight opening means of the invention is shown generally at 4. 5 is the flap in the frame formed

by a line of weakening 9, and 6 is an opening tab in the flap.

In Figure 2 the method of securing the transparent sheet is best illustrated. This sheet shown at 7 is adhesively secured to the frame 4 along a line not shown but contiguous to the opening 8 in the bag. This frame 4 is then adhesively secured directly to the side of the bag outside of the line of attachment of the frame to the transparent sheet and approximately at the outer extremity of the frame.

The transparent sheet 7 is preferably formed from Cellophane but other transparent materials such as oiled paper, oiled silk or the like are entirely acceptable.

The flap 5 which is formed from the frame by providing a line of weakening 9 configurated generally as indicated may be opened or shut along a hinge line 10. This flap may include a tab member such as 6 which facilitates the opening of the flap. The flap is shown in open position in Figure 4.

When the flap 5 is in closed position as shown in Figure 2 it tends to remain closed because of the friction between the sides. In the practical use of the bag it is not necessary to open the flap more than a few times so the hinge line 10 is sufficiently strong for the purpose intended.

The sight opening construction of the invention facilitates the construction of the bag. The frame portion 4 and the transparent sheet 7 may be first assembled as a single unit. It is then a

simple hand operation to secure this unit adhesively to the bag 1. Preferably, the bag will have a preformed aperture corresponding exactly to the flap and it is a very simple matter to place the frame so that the edges of the flap coincide with those of the opening.

The improvement described is a simple one but of determined utility in the particular field to which it is limited. It provides a definite solution for the most troublesome of the problems involved in constructing a sight opening of the type indicated.

Having described my invention, I claim:

In a garment storage bag having an outer surface which is relatively resistant to the reception of an adhesive an aperture formed in said outer surface, a sight window assembly comprising a relatively stiff frame member formed from paper board or the like and having an opening therein, a transparent sheet having a relatively slick surface adhesively secured to the inner surface of the frame member and disposed across the opening in such a way as to leave outer marginal portions of the frame member not contacted by said transparent sheet and a flap portion in said frame member for closing the opening therein; said assembly being adhesively secured to the outer surface of the garment bag solely along the said outer marginal portions of the frame member and with the opening in said frame member aligned with the aperture in the surface of the bag.

SAMUEL J. JOHNSON.
